(57) **CLAIM**

The ornamental design for a dock for a cryogenic device, as shown and described.

DESCRIPTION

FIG. 1 is an isometric view of a dock for a cryogenic device.

FIG. 2 is a back view of the dock of FIG. 1.

FIG. 3 is a front view of the dock of FIG. 1.

FIG. 4 is a left side view of the dock of FIG. 1.

FIG. 5 is a right side view of the dock of FIG. 1.

FIG. 6 is a top view of the dock of FIG. 1; and,

FIG. 7 is a bottom view of the dock of FIG. 1.

The broken lines in the drawings illustrate portions of the dock for a cryogenic device which forms no part of the claimed design.
